COMBINATION CLAMP AND DRIFT PIN

Filed Jan. 24, 1930

UNITED STATES PATENT OFFICE

ALEXANDER Q. NASH, OF CINCINNATI, OHIO; GEORGE W. STEVENSON, ADMINISTRATOR OF SAID ALEXANDER Q. NASH, DECEASED, ASSIGNEE TO CIRCULAR CONCRETE CONTAINER CORPORATION, OF CINCINNATI, OHIO, A CORPORATION OF OHIO

COMBINATION CLAMP AND DRIFT PIN

Application filed January 24, 1930. Serial No. 423,171.

This invention is directed to a combination clamp and drift pin designed more particularly for use in connection in assembling and relatively fixing the sections of shell molds used in cement or like molding.

In building structures of cement or like plastic material it is usual to provide a shell-like mold to receive and form the plastic material, and, particularly in large constructions, these shell molds are made up of sections with edges of angle-iron or like reinforcement. In previous constructions these sections of the mold are assembled and held in mold-forming relation by bolts passed through openings in the outstanding margins of the angle-iron edges and held by nuts tightened on the bolts during the molding operation. The time required to place and remove the nuts and bolts, to say nothing of the difficulty incident to holding the sections in proper relation to align the bolt holes of adjacent sections, rendered the work of assembling and dismantling the molds a difficult and expensive detail of the building operation.

The primary object of the present invention is to materially simplify and reduce the time and expense of both assembling and dismantling the mold sections through provision of a single element serving as a combined drift pin and clamp, and through the use of which the sections are assembled in proper relation by use of the drift pin feature of the element and the angle-iron elements of the sections securely and relatively clamped to hold the mold sections in mold-forming relation, through which both the assembling and dismantling of the mold sections may be carried out in a speedy and convenient manner, with a consequent saving of time and expense.

The improvement, structurally considered, comprises an integral element formed to provide relatively convergent clamping jaws with an extended handle, one of the jaws being extended and provided with a fixed drift pin; so that the drift pin, when used to draw the sections together thereafter becomes the pivot on which the element is rotated to force

the jaws into clamping relation with the angle iron sections or free the sections.

The invention is illustrated in the accompanying drawings, in which:

Fig. 1 is a perspective view, showing the improved clamping element in operative relation with the angle-iron margins of a mold section.

Fig. 2 is a plan of the same.

Fig. 3 is an edge view of the same, the mold sections being shown in section.

Fig. 4 is a perspective view of the improved clamp.

Fig. 5 is a transverse section through the clamp in operative position.

The improved clamp comprises an integral metallic body 1, having a U-shaped portion 2, the side walls of which, as 3 and 4, have their inner surfaces relatively convergent, as indicated more particularly in Fig. 5. The clamp includes a handle section, extended from the upper part of the U-shaped portion, such handle section, indicated at 5, projecting at substantially a right angle from the portion 2, and forming a substantial, rigid, and strong extension.

One of the walls of the U-shaped portion 2 of the clamp is extended forwardly for a portion of the height of such wall, this extension 6 projecting in the plane of the wall of the portion 2 from which it extends, and being thus at one side of the clamping space between the side walls 3 and 4. This extension 6 is provided with a rigid drift pin 7, projecting at right angles to the plane of the extension, and of course tapering toward its free end. The drift pin has a length exceeding the transverse dimension of the clamp proper.

The improved clamp, while of course capable and intended for any use to which it may be put, is primarily designed for positioning and clamping mold sections in concrete or like molding. As illustrated such molds are made up of sheet metal sections 8, having angle-iron reinforcements 9 at their marginal edges. These angle irons are secured to present an outstanding flange 10, and in assembling the sections 8, the flanges 10, both vertically and horizontally of the

sections are placed in contact and are designed to be secured together, both in annular formation and in superimposed relation. These flanges 10 are formed with openings 11, and in assembling the sections, as heretofore proposed, these openings of the respective flanges 10 are brought into proper relation by drift pin action, and bolts passed through such aligned holes and secured by nuts. The difficulty of holding the holes in the flanges 10 aligned after use of the drift pin and while inserting the bolts, together with the time consuming operation of applying the bolts and nuts in assembling and removing same in dismantling, added a very material expense to the ultimate molding operation.

The present improvement avoids all the difficulties, and so reduces the time necessary to the operation, as to render the assembling and dismantling a comparatively minor item of time or expense. In use, when the sections are initially arranged in proper relation, the drift pin is driven through the appropriate holes in the meeting flanges 10, and such holes brought into alignment, thus properly positioning the adjacent mold sections. Then, without removing the drift pin and thereby holding the sections of the mold in their proper relation, the clamp as a whole is turned on the drift pin as a pivot, and the jaws of the clamp forced to embrace the meeting flanges 10. This operation, by reason of the convergence of the walls of the portion 2 of the clamp, forces the flanges 10 into fixed and close contact, and secures the mold sections in desired relation. Of course, the separation of the clamp, when dismantling the sections, is carried out in an obvious manner.

The clamp thus provides for drift-pin arrangement of mold sections and subsequent clamping of such sections in fixed relation in a simple speedy operation, requiring only a sufficient number of the clamps and a member for driving the drift pins, and the clamps can be continually reused. The clamps are of course to be constructed of rugged metal to stand the specified usage, though they may be of any size requisite for the particular mold. The handle 5 is sufficiently strong to permit driving, thus insuring that force may be used if desired to insure a proper clamping action even under a slight distortion of the flanges 10, as may in fact occur in repeated use of the mold sections. The handle, by reason of the plane of its projection relative to the clamping section 2, will, when in clamping relation, rest closely adjacent the free edges of the angle-iron sections 10, as shown in Fig. 1, thus avoiding undue projection, while at the same time permitting free access to the handle for removing the clamp when desired.

Having thus described the invention, what is claimed as new, is:—

1. A combined clamp and centering pin for use in aligning the bolt holes in the flanges of molding sections and for clamping said sections with relation to each other after bolt hole alignment including a member having jaws to form a clamp for the flanges, and a cylindrical tapered pin depending from one of said jaws to cooperate with and align the bolt holes of superimposed flanges and to serve as a pivot pin for the operation of the clamp following such aligning function. 70

2. A combined clamp and centering pin including an element formed to provide clamping jaws, and a cylindrical tapered pin carried by the element wholly beyond the clamping jaws whereby the pin may be used as a centering pin without jaw interference and thereafter serve as a pivot for clamping movement of the jaws. 80

3. A clamp including a U-shaped clamping section providing clamping jaws, one of the jaws being extended, and a cylindrical tapering pin fixed in such jaw extension. 85

4. A combined clamp and centering pin operating to center the bolt holes in the lateral flanges of superimposed molding sections and to clamp the flanges together, comprising a clamping member formed to embrace the superimposed flanges and clamp them in fixed relation, and a pin carried by said member of cylindrical tapered form, said pin being operative to initially and perfectly align the bolt holes of the superimposed flanges and following such aligning operation serve as a pivot for the operative movement of the clamp with respect to such flanges while maintaining the aligned relation of the bolt holes. 100

In testimony whereof I affix my signature.
